UNITED STATES PATENT OFFICE.

WILLIAM C. F. MICHEL, OF WALDO, OHIO.

ICE-CUTTING MACHINE.

No. 920,166.

Specification of Letters Patent.

Patented May 4, 1909.

Application filed April 10, 1908. Serial No. 426,416.

To all whom it may concern:

Be it known that I, WILLIAM C. F. MICHEL, a citizen of the United States, residing at Waldo, in the county of Marion and State of Ohio, have invented certain new and useful Improvements in Ice-Cutting Machines, of which the following is a specification.

My invention relates to ice cutting machines, and has for its object the provision of 10 a device of this character provided with a plurality of saws, one of said saws cutting the ice into longitudinal strips, another of said saws cutting said strips into blocks and a third saw cutting a guide groove in the ice 15 to guide the machine in its succeeding trip across the ice.

A further object of the invention is the provision of improved means for automatically stopping the machine, after a predetermined movement until the block cutting saw has completed the cutting of a block from the strip and also of improved means for bodily elevating the machine at the end of a trip to facilitate its movement to a position to begin the next cut.

Further objects and advantages of the invention will be set forth in the detailed description which now follows.

In the accompanying drawings: Figure 1 is a plan view of the machine, Fig. 2 is a side elevation, Fig. 3 is an end elevation, Fig. 4 is a section on line $x-x$ of Fig. 1, looking in the direction of the arrow, Fig. 5 is a detail view of the driving means or an automatic stop wheel, and, Fig. 6 is a view showing means for holding the saw that cuts the ice into strips, at any determined height.

Like numerals designate corresponding parts in all of the figures of the drawing.

40 In the drawing, the numeral 1 designates a framework which is adapted to rest upon the ice and which supports a gasoline engine 2, the side members of the frame serving as runners in the movement of the machine. 45 Upon one end of the framework are located bearing blocks 3 which support a shaft 4. This shaft in turn supports arms 5 and a pulley 6, said arms 5 having a swinging movement upon the shaft. Mounted in the outer ends of the arms 5 is a second shaft 7. This shaft carries upon one end the large circular saw 8 and upon its opposite end the smaller circular saw 9. The circular saw 8 is designed to saw the ice into strips and the small saw 9 is designed to saw a groove in the surface of the ice so that the machine in

making the next cut, will be guided by this groove. A small pulley 10 is also mounted upon the shaft 7 and is connected with the large pulley 6 by means of a belt 11. Connected with the shaft 4 by means of a pulley 12 is a belt 13 which connects with the pulley 14 of the gasoline engine. Upon one end of the shaft 4 is a bevel pinion 15. This pinion engages with a pinion 16 which is mounted upon a shaft 17 (see Figs. 1 and 3). This shaft 17 is mounted in bearing blocks 18 and upon the shaft 17 arms 19 are mounted. A shaft 20 is journaled in the outer ends of arms 19, said arms having a swinging movement from shaft 17. Carried by shaft 20 is a circular saw 21. This circular saw 21 is adapted to saw the blocks of ice from the strip of ice cut by the saw 8. A small pulley 22 is mounted upon shaft 20 and power is transmitted to this pulley by means of a belt 23 and large pulley 24, which is mounted upon the shaft 17.

Upon the crank shaft 25 which in this case is made long and is supported by a bearing 26 upon an inclined bearing arm 27, is mounted a friction pulley 28. This friction pulley has upon its inner side next to the motor a groove in which a belt 29 is adapted to run. A second friction pulley 30 is located behind the first named friction pulley and is similar in construction. A third friction pulley 31 is mounted between the pulleys 28 and 30 and is adapted to be forced into frictional engagement with either the pulley 28 or the pulley 30. The friction pulley 31 is mounted upon a shaft 32, which at one end is mounted in a bearing 33, the outer end of the shaft being supported in a movable bearing 34, and the bearing 33 permitting a slight lateral movement of shaft 32. This movable bearing 34 comprises a support 35 which is pivoted as at 36 to the arm 27. To one end of the bearing support 35 is connected a link 37; this bar being pivoted to the handle or controlling lever 38. The lever 38 is in turn pivoted at 39 upon an upright post 40. It will thus be seen that if the handle 38 is moved either to the right or to the left, it will force the friction pulley 31 either into engagement with the friction pulley 28 or friction pulley 30, thereby causing the shaft 32 to revolve either in one direction or in the other.

In order to transmit motion to the entire machine, a bevel pinion 41 is securely fastened to the shaft 32 and meshes with a sec-

ond bevel pinion 42 mounted upon a shaft 43. A worm 44 is fixedly mounted upon one end of shaft 43. This worm in turn meshes with a worm wheel 45 which is mounted upon a shaft 46 carrying upon its extreme end a sprocket wheel 47, said sprocket wheel 47 being connected with a second sprocket wheel 48 by means of a chain 49. The sprocket wheel 48 is mounted 10 upon a shaft 50, upon which shaft is mounted a roller 51 having a number of spikes or teeth 52 securely fastened thereto. These teeth are to project into the ice to propel the machine forward or backward. A foot lever 53 15 is pivoted near one end, as at 54, and is pivotally connected with a yoke bar 55, which is more clearly shown in Fig. 5 of the drawing. This foot lever 53 is for the purpose of raising the worm wheel 45 into engagement 20 with the worm 44.

By referring to Fig. 5, it will be seen that two of the teeth of the worm wheel are shorter than the others. The reason for making these teeth shorter is this: Assume 25 that a block of ice is to be cut from the strip and the machine is stopped so that the cut-off saw 21 may be lowered to cut off the desired block. After this has been done, it is desired to move the machine forward just 30 far enough to cut off a second block. In most cases, blocks of ice are cut about 20 inches square, therefore it will be seen that the entire machine must move forward just 35 20 inches and stop. In order to do this the foot lever 53 is pressed at one end, which forces the worm wheel 45 up so that the short teeth will become engaged with the worm wheel 44. Just as soon as these teeth engage the worm, the machine starts to travel 40 forward. As soon as the machine gets under way, or has traveled a few inches, the foot lever 53 is released so that the worm wheel 45 drops to its original position, but by this time the long teeth are in engagement with 45 the worm, so that the travel of the machine is continued. Now, as soon as the 20 inches is traveled, the short teeth come opposite or below the worm 44 and therefore are not in 50 engagement with the worm wheel 45 and the machine is automatically brought to a stop to permit the cutting off of another block.

In order to raise and lower the cut-off saw 21, a second lever 56 is used, this lever being pivoted to the post 40 as at 57. Connected 55 to the lower end of the lever 56 is a link 58, the opposite end of which is connected to one of the arms 19. It will be seen that by raising upon the handle of the lever 56, the cut-off saw 21 will be lowered, therefore sawing 60 into the block of ice and cutting it free from the main strip. A seat 59 is provided for the operator, who rides upon the machine.

In order to keep the machine from getting 65 out of the desired position in moving across the ice, the saw 9 cuts a groove and upon the

framework of the machine I have provided, at its forward end, a guide plate 60 and at the rear end a similar guide plate 61. In order to set the circular saw 8, so that it will cut only to a desired depth, I have provided 70 upon each side of the arms 5 a lag screw. This screw extends into the arm for only a small distance and upon the bearing post 3 is a lug 62. A circular arm 63 is pivoted in the lug 62 and upon each side of the arm 5. 75 A rod 64 connects the two circular pieces 63 at their upper ends. Upon one face of the segment 63 are a number of notches 65. These notches engage with the lag screws and hold the arms in the desired position. 80 Now, in order to set the saw at any elevation, a rope or cord 66 is connected with one of the arms 5 as is shown in Figs. 1 and 4 of the drawing. This rope extends downward from the arm 5 through a small pulley 85 located upon the framework and from there up to the seat post. In order to set the saw, it is necessary to grasp this rope and pull up upon it and at the same time lean forward and throw the arms 64 back out of engagement with the lag screws and then raise or lower the saw, allowing the arm 63 to come back to its original position and engage the lag screws with the notches 65.

In order to move the saw or machine after 90 the machine has completed a cut across the ice, I have provided near its forward and rear ends, better shown in Fig. 2, a means for bodily elevating the machine. These means comprise blocks of wood 67 half the thickness of the frame, which are connected with the frame beams by the links 68 (see Fig. 4). Near the center of the frame and the bar, are lag screws 68 which extend into the wood only a short distance. A lever 69 which has 100 one end bent is adapted to pass over the lag screws in such manner that when a downward pull is exerted upon the lever 69, it will cause the bars 67 to be forced downward, and raising the machine up off of the ice by 105 bringing the links to a substantially vertical position. These bars 67 will be forced back against the side frame, so that the links 68 will be a little beyond their centers. There will, therefore, be no danger of the machine 110 running until after the bars 67 have been returned to their original position. The shaft 46 upon which the worm wheel 45 is mounted, as is shown in Fig. 2 of the drawing, has an elongated bearing. This is to permit said 115 shaft to be forced up until the short teeth on the worm wheel 45 mesh with the worm 44. It is also to be understood that the bearing 33 must be so constructed as to allow a little side movement, so that in forcing the friction 120 disk 31 against either of the friction disks 28 or 30, it will not bind.

The operation of the device is as follows: The gasoline engine having been set in operation, the foot lever 53 is depressed and the 125

handle 38 is thrown to the right or left according to the direction in which it is desired to have the machine travel. After the machine starts, the foot lever is released 5 and the machine will only cut a strip of the desired length before automatically coming to a stop. The operator then lowers the cut-off saw through the connections described and cuts off the block. The machine is again started and this operation repeated until the machine has traveled across the body of ice to be cut. The body of the machine is then elevated by lever 69 and the bars 67 rest upon the ice and serve as runners as the machine is forced away from the previously formed cut at right angles to its former line of travel to bring the guide members 60 and 61 into alignment with the guide groove cut by the saw 9.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth. For instance, I desire to have it understood that some other form 50 of motive power than the gasoline engine may be provided and various other modifications may be made, within the scope of the appended claims.

What I claim is,

1. In an ice cutting machine, the com-

bination with a longitudinally cutting saw and a transversely cutting saw, of means for automatically stopping the machine after a predetermined movement to permit the transversely cutting saw to act, said means comprising a spurred driven member, a driving member, and a gear connection between said members comprising a worm and a worm wheel, some of the teeth of said worm wheel being shorter than others, and means for bodily elevating said worm wheel to bring its shortest teeth into mesh with the worm.

2. In an ice cutting machine, the combination with a frame, of a saw arranged to cut in the direction of travel of the machine, a second saw arranged to cut at right angles to the first named saw and a third saw arranged to cut a guide groove in the ice parallel to the cut of the first named saw, means for lifting all of said saws out of engagement with the ice, said frame comprising longitudinally extending runners and transversely extending runners connected to said frame by pivoted links and means for shifting said transverse runners to bring said links into vertical alignment to thereby bodily elevate the frame from said transverse runners.

In testimony whereof I affix my signature in presence of two witnesses,

WILLIAM C. E. MICHEL.
